FRED W. MAYER, OF CHICAGO, ILLINOIS.

GARMENT-RACK.

1,316,375.

Specification of Letters Patent. Patented Sept. 16, 1919.

Application filed October 28, 1918. Serial No. 259,980.

To all whom it may concern:

Be it known that I, FRED W. MAYER, a citizen of the United States of America, and a resident of Chicago, county of Cook, and

5 State of Illinois, have invented certain new and useful Improvements in Garment-Racks, of which the following is a specification.

The main objects of this invention are to 10 provide an improved form of rack for use in supporting hats, coats, and other garments on seats in public meeting-places; to provide an improved construction and arrangement of said rack whereby the hat is separately 15 supported from the other garments; to provide improved means for attaching the rack to a support whereby it is normally urged into a retracted position when not in use and may be readily extended when garments are 20 to be placed therein; to provide improved means on said rack so as to enable women's hats having little or no rims to be secured thereto; and to provide a rack of this kind which is simple and inexpensive in construction 25 and which may be readily attached to almost any form of seat.

An illustrative embodiment of this invention is shown in the accompanying drawings, in which—

30 Figure 1 is a sectional view of a simple form of folding theater seat, showing the improved rack attached to the seat member thereof.

Fig. 2 is a front view of the theater seat 35 with the seat member thereof in its upright folded position so as to present a bottom plan of the garment rack.

Fig. 3 is a front view of the seat member.

Fig. 4 is an enlarged sectional detail of 40 one of the extensible supporting devices by which the rack is suspended on the seat member.

The improved form of rack comprises a frame 1 attached by a plurality of extensible devices 2 to a support or seat member 3, said devices being constructed so as to normally urge said frame toward said support whereby said frame when not in use is retained in a retracted position relative to 45 said support and when in use yieldingly clamps the garments against dislodgment.

In the specific embodiment herein shown, the frame 1 is a wire construction comprising a perimetric wire preferably formed of 55 a single piece, the sides and back of which are substantially in the form of a U. The

front part of said perimetric wire is doubled in upon itself also substantially in the form of a U and is disposed in a plane slightly below that of the U-shaped formation of the 60 sides and back and substantially parallel thereto as appears from Figs. 1 and 3. Loops 4 are formed in said perimetric wire for the purpose of affording means for connecting with the extensible devices 2. These 65 loops are preferably at the sides near the front, and at the back near the middle, and are so disposed that the extensible members are located outside of the general contour of the perimetric wire.

In racks of similar character heretofore in use, the coat or other garment placed therein has been made to rest directly upon the brim of the hat, which has frequently resulted in injury to the hat. In the construction shown in the drawing, this injury is 70 obviated by providing a pair of intersecting cross wires 5 disposed substantially in the plane of the U-shaped formation of the sides and back of the perimetric wire. The cross 75 wire contacting with the perimetric wire are adapted to support garments between the same and said support, whereas the doubled-in part of the perimetric wire serves as a support for the hat with the brim of the hat 80 resting on the wire and the crown suspended below. As shown in Fig. 2, one end of each of the wires 5 is secured to the perimetric wire at the forward end thereof adjacent to the front pair of loops 4. The opposite end 85 of each of the wires 5 is passed over the diametrically opposite part of the perimetric wire and is then bent downwardly and back so as to be secured to the base part of the 90 U-shaped formation of the front part of the perimetric wire and provides a support for the rear end thereof.

The extensible means or devices 2 each 95 comprise a plurality of cylindrical members 6, 7, and 8 telescopingly arranged one within the other. A spring 9 is located between the members 6 and 7 so as to embrace the latter, and a second spring 10 is located within the member 7 so as to embrace the member 8. The members 7 and 8 are provided 100 with heads 11 and 12 respectively formed on the inner ends thereof, and the members 6 and 7 are formed with shoulders 11' and 12' at their lower ends. The springs 9 and 10 bear against the respective heads and shoulder and normally urge the respective members into their retracted positions. Screws 105

13 are carried on the outer ends of the members 8. The stem of each of these screws is adapted to pass through one of the loops 4 and be screwed into the end of a member 8 5 for the purpose of securing the wire frame 1 to the respective supporting devices. The loops 4 loosely embrace the screws 13 and also fit loosely between the heads of the screws and the members 8 as appears in 10 Fig. 4. This loose connection of the loops 4 to the screws prevents bending of the frame and supports when the rack is extended.

In order that the frame when not in use 15 may be held as closely as possible to the support 3 and yet at the same time allow for the maximum extension when it is to be used for retaining garments, the members 6 of the supporting devices 2 have flanges 14 formed thereon intermediate the ends. This 20 enables the supporting devices to be attached to the support 3 with about half of each of the members 6 extending through holes in the support 3 up into the upholstery of the seat. The flanges 14 are of course provided 25 with apertures through which screws or other fastening means may be inserted for the purpose of attaching the members 6 to said support. Thus the members 6, 7, and 8 may be longer than would be the case if the 30 outer members were to be attached directly to the bottom of the support 3. The result is that, when not in use the frame is held well up against the seat, but may be extended to accommodate a very large folded-over 35 garment, as will be obvious from Fig. 1.

The support 3 is herein shown in the form of a seat member, being a part of a folding seat and pivotally attached at 15 to a bracket 16 so that it may be folded up against the 40 back member 17 when the seat is not in use.

A knob or handle 18 is secured to the cross wires 5 at the intersection thereof for the purpose of providing means for enabling one to grip the frame when it is to be pulled 45 out away from the support 3 to allow garments to be deposited between the cross wires and said support. This knob 18 also serves as an obstruction to prevent the hat from being accidentally dislodged from the 50 frame. The reason for this is that when the hat is set in on the frame it is necessary to tip the rear edge thereof (relative to its position on the rack) downwardly a little so as to allow said rear edge to pass the knob. 55 Having been thus placed on the rack the hat cannot be removed without again tipping it slightly to pass the knob,—which tilting cannot occur accidentally.

The member 18 is provided with a plurality 60 of apertures 19 extending diametrically therethrough, through which hat pins may be inserted when it is desired to secure a woman's hat in the rack where the hat is without a brim of sufficient size to rest on 65 the frame, as in the case of a toque.

When the rack is not in use, it is normally urged into a retracted position relative to the seat member 3, substantially as indicated in Figs. 1 and 3. When one desires to place a garment such as an overcoat, and a hat, 70 therein, the coat is folded up and, with one hand grasping the knob 18 and pulling the frame out away from the seat 3, the coat is placed in upon the cross-bars 5 below the seat 3. The hat may also be placed in the 75 rack so that the brim thereof rests upon the doubled-in front portion of the perimetric wire, with the crown suspended below.

Although but one specific embodiment of this invention has been herein shown and 80 described, it will be understood that numerous details of the construction shown may be altered or omitted without departing from the spirit of this invention as defined by the following claims. 85

I claim:

1. The combination with a seat, of a garment rack comprising a frame, extensible means supporting said frame on said seat, said extensible means each comprising a plurality of hollow members nested one within the other, the outermost member being secured to the seat and the innermost member being connected to said frame, and springs interposed between each pair of said members and independently urging the respective members into their nested relation whereby said frame is normally urged toward said seat, so that when said rack is not in use it is retained in a retracted position 100 against said seat and when in use yieldingly clamps the garments between said frame and seat. 90

2. The combination with a seat, of a garment rack comprising a frame, extensible means supporting said frame on said seat, said seat having holes formed therein, said extensible means each comprising a plurality of cylindrical members nested one within the other, the outermost member being provided with a flange intermediate its ends whereby said outer member is secured to the seat with the one end extending into said seat and the other end extending out from said seat, and the innermost member being 110 connected to said frame, and springs interposed between each pair of said members and independently urging the respective members into their nested relation whereby said frame is normally urged toward said seat, so that when said rack is not in use it is retained in a retracted position against 115 said seat and when in use yieldingly clamps the garments between said frame and seat. 120

3. The combination with a seat, of a garment rack comprising a wire frame, extensible means supporting said frame on said seat, said extensible means each comprising three or more cylindrical members nested one within the other, the outermost member 130

- of each of said means being secured to the seat, the innermost member of each of said means having removable fastening means thereon and extending through the respective loops so as to secure said frame to said innermost members, and springs interposed between each pair of said members and independently urging the respective members into their nested relation whereby said frame is normally urged toward said seat, so that when said rack is not in use it is retained in a retracted position against said seat and when in use yieldingly clamps the garments between said frame and seat.
- 5 4. A garment rack for seats, comprising a support, a three-piece wire frame, one of said pieces having the sides and back thereof bent substantially in the form of a **U** and disposed in one plane, the front of said frame being doubled in upon itself also substantially in the form of a **U** and disposed in another plane, the other two pieces being secured at their forward ends to the front portion of said one piece, crossed in the plane of said sides and back and attached to said back, and then brought forward and attached to the rear of said doubled-in portion.
- 10 5. A garment rack for seats, comprising a support, a wire frame, said frame having the sides and back thereof bent substantially in the form of a **U** and disposed in one plane, the front of said frame being doubled in upon itself also substantially in the form of a **U** and disposed in another plane, cross-wires disposed in the plane of said sides and back and adapted to support garments between said wires and said support, said extensible means each comprising a plurality of cylindrical members nested one within the other, the outermost member being provided with a flange intermediate its ends whereby said outer member is secured to the seat with the one end extending into said seat and the other end extending out from said seat, and the innermost member being connected to said frame, and springs interposed between each pair of said members and independently urging the respective members into their nested relation whereby said frame is normally urged toward said seat so that when said rack is not in use it is retained in a retracted position 15 against said seat and when in use yieldingly clamps the garments between said cross bars and seat.
- 20 6. The combination with a seat, of a garment rack comprising a wire frame, extensible means supporting said frame on said seat, said seat having holes formed therein, said frame having the sides and back thereof bent substantially in the form of a **U** and disposed in one plane, the front of 25 said frame being doubled in upon itself also substantially in the form of a **U** and disposed in another plane, cross-wires disposed in the plane of said sides and back and adapted to support garments between said wires and 30 said support, said extensible means each comprising a plurality of cylindrical members nested one within the other, the outermost member being provided with a flange intermediate its ends whereby said outer member is secured to the seat with the one end extending into said seat and the other end extending out from said seat, and the innermost member being connected to said frame, and springs interposed between each pair of 35 said members and independently urging the respective members into their nested relation whereby said frame is normally urged toward said seat so that when said rack is not in use it is retained in a retracted position 40 against said seat and when in use yieldingly clamps the garments between said cross bars and seat.
- 25 7. The combination with a seat, of a garment rack comprising a wire frame, extensible means supporting said frame on said seat, said seat having holes formed therein, said frame having the sides and back thereof bent substantially in the form of a **U** and disposed in one plane, the front of 50 said frame being doubled in upon itself also substantially in the form of a **U** and disposed in another plane, cross-wires disposed in the plane of said sides and back and adapted to support garments between said wires and 55 said support, said extensible means each comprising a plurality of cylindrical members nested one within the other, the outermost member being provided with a flange intermediate its ends whereby said outer member is secured to the seat with the one end extending into said seat and the other end extending out from said seat, and the innermost member being connected to said frame, and springs interposed between each pair of 60 said members and independently urging the respective members into their nested relation whereby said frame is normally urged toward said seat so that when said rack is not in use it is retained in a retracted position 65 against said seat and when in use yieldingly clamps the garments between said cross bars and seat.
- 30 8. The combination with a seat, of a garment rack comprising a wire frame, extensible means supporting said frame on said seat, said seat having holes formed therein, said frame having the sides and back thereof bent substantially in the form of a **U** and disposed in one plane, the front of 70 said frame being doubled in upon itself also substantially in the form of a **U** and disposed in another plane, cross-wires disposed in the plane of said sides and back and adapted to support garments between said wires and 75 said support, said extensible means each comprising a plurality of cylindrical members nested one within the other, the outermost member being provided with a flange intermediate its ends whereby said outer member is secured to the seat with the one end extending into said seat and the other end extending out from said seat, and the innermost member being connected to said frame, and springs interposed between each pair of 80 said members and independently urging the respective members into their nested relation whereby said frame is normally urged toward said seat so that when said rack is not in use it is retained in a retracted position 85 against said seat and when in use yieldingly clamps the garments between said cross bars and seat.

Signed at Chicago this 25th day of Oct., 1918.

FRED W. MAYER.
